[57] CLAIM

The ornamental design for a carrying case, as shown and described.

DESCRIPTION

FIG. 1 is a perspective view of a carrying case showing my new design;

FIG. 2 is a front elevational view;

FIG. 3 is a right side elevational view;

FIG. 4 is a rear elevational view;

FIG. 5 is a top plan view; and

FIG. 6 is a bottom plan view.

The drawing is shaded to illustrate that the front, rear, top and bottom panels are of a material having the appearance of wood.
